H. F. HOEHNE.
THISTLE PULLING MACHINE.
APPLICATION FILED SEPT. 24, 1917.

1,267,073.

Patented May 21, 1918.

UNITED STATES PATENT OFFICE.

HERMAN FRED HOEHNE, OF KAUKAUNA, WISCONSIN.

THISTLE-PULLING MACHINE.

1,267,073.

Specification of Letters Patent. Patented May 21, 1918.

Application filed September 24, 1917. Serial No. 192,965.

To all whom it may concern:

Be it known that I, HERMAN F. HOEHNE, a citizen of the United States, residing at Kaukauna, in the county of Outagamie and

5 State of Wisconsin, have invented certain new and useful Improvements in Thistle-Pulling Machines; and I do declare the following to be a full, clear, and exact description of the invention, such as will enable 10 others skilled in the art to which it appertains to make and use the same.

My invention relates to improvements in thistle pulling machines, or weeders, of the general type shown in the U. S. patent to 15 Bornemann & Tennessen, Jr., 1,136,206 of April 20, 1915. This machine has met with much success, but experience has taught that some improvement is necessary to prevent bending of the comb teeth and breaking of 20 the cleaner springs.

In the machine illustrated in the patent above referred to, the comb teeth decrease in width toward their outer ends and all of said teeth are of the same length, so that 25 wedge shaped spaces are provided between them to receive the thistles and weeds as the combs are rotated by the reel. It has been found that the larger weeds will not move toward the bases of the teeth before the pulling operation takes place, and this places all strain on the outer ends of the teeth. Since these ends are remote from the points of anchorage of the teeth, and are rather delicately shaped, bending of the teeth often 30 takes place. One object of my invention, therefore, is to provide a comb in which alternate teeth are of less length than the intervening teeth, whereby the weeds may move toward the bases of these teeth before 35 being gripped thereby, thus insuring that no bending shall take place.

A further disadvantage of the machine in question, is that the cleaners for the combs must move to such an extent as to place excessive strain upon the springs which return 45 them to their initial positions. This has caused considerable trouble by breaking these springs. A further object of the invention is to overcome this difficulty by 50 shortening the travel of the cleaners, this being permitted by the arrangement of teeth above set forth.

With the foregoing general objects in view, the invention resides in the novel features of construction and unique combinations of parts to be hereinafter fully de-

scribed and claimed, the descriptive matter being supplemented by the accompanying drawings which form a part of this specification and in which:

Figure 1 is a perspective view of a portion of a weed puller embodying the improved combs;

Fig. 2 is a detail vertical longitudinal section of the machine;

Fig. 3 is a plan view of one section of the improved comb;

Figs. 4 and 5 are transverse sections of Fig. 3 on the planes of the lines 4—4 and 5—5 respectively; and

Fig. 6 is a perspective view of one section of the comb.

In the drawings above briefly described, the numeral 1 designates the frame of the machine, said frame being mounted upon suitable wheels 2 which drive a rotating reel 3, by means of gearing or other suitable driving connections. The reel 3 includes a plurality of circumferentially spaced bars 4 parallel with the reel axis, a cleaning bar 5 adjacent each bar 4, actuating levers 6 for said bar 5, stops 7 on the frame 1 for actuating said levers to cause the bars 5 to clean the combs yet to be described, and springs 8 for returning said levers to their initial positions. All of this construction is well known and forms no part of the present invention, being illustrated solely for the purpose of disclosing the application of the improved combs 9 to the reel 3.

Each comb 9 is provided with a plurality of teeth of unequal length, the alternate teeth 10 being longer than the intervening teeth 11, the former being preferably about twice the length of the latter. The teeth 10 and 11 are preferably formed integrally with the front edge of an attaching base or plate 12 which is secured by bolts or the like to the adjacent bar 4 of the reel 3, stamped metal construction being in most cases employed. During the stamping operation, the edges of the several teeth, which edges converge toward the outer ends thereof, are turned downwardly to a slight extent to provide reinforcing flanges 13 which effectively stiffen the teeth. Each comb may be formed of a plurality of separate teeth if occasion should so demand, or of one piece extending throughout the length of the bar 4, but in most cases I prefer to form said combs in a plurality of sections as shown in Fig. 1, all of said sections being identical in shape

and construction in order that complications in manufacture and application may be avoided.

By the provision of the short teeth 11 between the teeth 10, the large weeds are permitted to move toward the bases 14 of the teeth, before they are wedged between said teeth, and thus the strain of pulling is placed upon the strongest portions of the teeth, so that bending thereof is positively prevented. Furthermore since the function of the cleaners 5 is only to dislodge the weeds from the V-shaped spaces between the several teeth, these cleaners need only travel a distance equal to the length of the short fingers 11. By this reduction in travel, the strain upon the springs 8 is not so great as in the original machine, and consequently there is no danger whatever of breaking these springs.

From the foregoing, taken in connection with the accompanying drawing, it will be obvious that although my invention is of comparatively simple and inexpensive nature, it will be highly efficient and durable

for the purposes intended. Since probably the best results are obtained from the several specific details shown and described, these details are by preference employed, but I wish it understood that within the scope of the invention as claimed, numerous minor changes may well be made.

I claim:

A comb for application to the rotating reel of a weed pulling machine, said comb having teeth decreasing in width toward their outer ends and having alternate teeth of less length than the intervening teeth to permit the weeds to move toward the bases of the teeth before they are wedged between the same, whereby bending of the teeth is prevented.

In testimony whereof I have hereunto set my hand in the presence of two subscribing witnesses.

HERMAN FRED HOEHNE.

Witnesses:

H. S. FAUST,
G. W. RISTAN.
